By Attorney

UNITED STATES PATENT OFFICE.

SAMUEL P. WELCH, OF ATLANTIC CITY, NEW JERSEY, ASSIGNOR TO OJUS SPARK PLUG WORKS, OF ATLANTIC CITY, NEW JERSEY, A PARTNERSHIP COMPOSED OF JOHN BURT AND SAMUEL P. WELCH.

SPARK-PLUG.

1,348,913.

Specification of Letters Patent. Patented Aug. 10, 1920.

Application filed July 12, 1919. Serial No. 310,514.

To all whom it may concern:

Be it known that I, SAMUEL P. WELCH, a citizen of the United States, residing at Atlantic City, in the county of Atlantic and 5 State of New Jersey, have invented new and useful Improvements in Spark-Plugs, of which the following is a specification.

This invention relates to spark plugs employed in connection with internal combustion engines for igniting the fuel charges in the cylinders, and its object is to provide a novel and improved plug in which the sparking terminals are arranged to produce more than one spark as will be described in detail hereinafter and claimed. 15

In order that the invention may be better understood, reference is had to the accompanying drawing forming a part of this specification, and in said drawing,

20 Figure 1 is a central longitudinal section of the plug, and

Fig. 2 is a perspective view of a fragment of the core of the plug.

Referring specifically to the drawing 5 25 denotes the core of the plug, the same being housed in the usual metallic base shell 6 which is constructed to screw into the engine cylinder. The usual lock nut 7 is also provided for holding the core in the shell.

30 These parts are all of standard design and construction, and hence a further description thereof is not deemed necessary.

The core 5 is made of porcelain, mica or other suitable insulating material, and in it 35 is embedded the main electrode rod 8 projecting from both ends thereof, its outer end being provided with the usual means for connection of the current wire.

At the inner or cylinder end of the core 40 5, the latter carries two conducting rings 9 and 10, respectively, said rings encircling the core and being fixed thereto in any suitable manner. The ring 9 has an electrode branch 11 extending downward and 45 laterally to come opposite the end of the rod 8, and spaced from the latter a distance to enable the electric current to jump across the gap. The ring 10 is not in contact with the ring 9 and it is located back of the latter such a distance that the current can 50 jump the gap between the two rings. From the ring 10 the current jumps the gap between the same and the inner or cylinder end of the shell 6, this end of the shell

encircling the ring in spaced relation. It 55 will be noted that the current cannot jump from the ring 9 directly to the shell 6 as the distance is too great and the ring 10 is also located directly between the ring 9 and the shell, in view of which it will be evident 60 that the current entering the ring 9 must jump first to the ring 10 and then to the shell 6.

The plug produces three separate and distinct series sparks, the first spark occurring 65 between the electrodes 8 and 11, the next between the rings 9 and 10, and the last between the ring 10 and the grounded shell 6. One or more sparks are assured, and if one or two gaps get clogged with carbon or oil, the plug is not short-circuited as there remains still another gap to fire. The plug can become short-circuited only if 70 all three gaps become clogged, which is a very remote contingency. Ordinarily, only 75 one gap is apt to get clogged, but as the plug continues to fire, the carbon or other deposit are quickly burned away and the gap is restored. The plurality of gaps also serve to intensify the sparks, and the ignition 80 of the fuel charges is more reliable and rapid, with an attendant saving of fuel and an increase of power and a better running of the engine.

It will be noted that the ring 10 is larger 85 and has a greater cross-sectional area than the ring 9. The ring 10 is therefore a better conductor than the ring 9 and as it is outside the latter it attracts the current in a lateral direction, and as the shell 6 surrounds the ring 10, the current is again drawn in a lateral direction across the gap between said ring and the shell. The heating effect of the sparks on the fuel is therefore in a direction to cause expansion in the 95 direction of the piston travel instead of transversely thereof. As the ring 10 is inside the shell 6, the current is induced to jump to the nearest ground which is the shell, and the spark once more passes through 100 the fuel charge by jumping straight across the bottom of the plug to the shell.

The ring 9 is adjustable to the main electrode 8 by bending the point 11, and this first gap may be closed entirely without 105 affecting the other gaps, if the ignition system should be too weak to furnish enough current for all three gaps. All adjustment

can be made on the core 5 before inserting the same into the shell 6.

I claim:

1. A spark plug comprising an insulating core, a metallic shell carrying the core, a main electrode rod carried by the core, and a pair of conductor rings carried by the core and spaced to produce a spark gap between said rings, one of the rings having a laterally projecting electrode which is so positioned with respect to the terminal of the main electrode rod as to produce a spark gap between said electrode and the rod and said laterally projecting electrode being pliable to permit bending into contact with the main electrode rod, and the other ring being spaced from the shell to produce a spark gap between said ring and the shell.

2. A spark plug comprising an insulating core, a metallic shell carrying the core, a main electrode rod carried by the core, and a pair of conductor rings carried by the core and spaced to produce a spark gap between said rings, one of the rings being positioned with respect to the terminal of the main electrode rod to produce a spark gap between said ring and the rod, and the other ring being spaced from the shell to produce a spark gap between said ring and the shell, said last mentioned ring having a greater conductivity than the first mentioned ring.

In testimony whereof I affix my signature.

SAMUEL P. WELCH.

Witness:

F. A. JONES.
